Filed Nov. 22, 1972, Ser. No. 308,922

Term of patent 14 years

Int. Cl. D6—01

U.S. Cl. D6—48

FIG. 1 is a perspective view of a combined automobile seat and recessed seat belt buckle showing my new design.

FIG. 2 is a top plan view of the buckle portion of the seat shown in FIG. 1.

FIG. 3 is a cross-sectional view as seen from the left side of FIG. 2.

FIG. 4 is another perspective view of the automobile seat showing my design with the buckle in operating position.

FIG. 5 is a cross-sectional view of the buckle portion of FIG. 4 as seen from the left side of FIG. 4.

The side of the article not shown is a mirror image of the side shown while the back is conventional.

I claim:

The ornamental design for a combined automobile seat and recessed seat belt buckle, as shown and described.
